CLAIM

The ornamental design for a shoe, as shown and described.

DESCRIPTION

FIG. 1 is a side view of a shoe.

FIG. 2 is another side view of the shoe of FIG. 1, from the opposite side of the shoe shown in FIG. 4.

FIG. 3 is a front view of the shoe of FIG. 1.

FIG. 4 is a back view of the shoe of FIG. 1.

FIG. 5 is a top view of the shoe of FIG. 1.

FIG. 6 is a bottom view of the shoe of FIG. 1; and,
FIG. 7 is a perspective view of the shoe of FIG. 1.

The dot-dash broken lines surrounding a portion of the shoe show a boundary that forms no part of the claimed design. Portions of the shoe outside of the dot-dash broken lines show environment that form no part of the claimed design.

1 Claim, 7 Drawing Sheets
